Specification for Design.

Patented Jan. 3, 1922.

Application filed December 30, 1920. Serial No. 434,144. Term of patent 14 years.

To all whom it may concern:

Be it known that I, HARRY Y. NORWOOD, a citizen of the United States, residing at Rochester, in the county of Monroe and State of New York, have invented a new, original, and ornamental Design for a Combination Hose Coupling and Valve, of which the following is a specification, and of which the accompanying drawing is a representation.

Figure 1 is a side elevation of a combination hose coupler and valve showing my new design.

Figure 2 is a top view of the same.

I claim:

The ornamental design for a combination hose coupling and valve, as shown.

HARRY Y. NORWOOD.
